(57) **CLAIM**

The ornamental design for shark-light for hand-held video game, substantially as shown and described.

DESCRIPTION

FIG. 1 is a perspective view of a shark-light for hand-held video game showing my new design;

FIG. 2 is a side elevational view thereof;

FIG. 3 is an opposite side elevational view of FIG. 2;

FIG. 4 is a front elevational view thereof;

FIG. 5 is a rear elevational view thereof;

FIG. 6 is a bottom plan view thereof; and,

FIG. 7 is a top plan view thereof.

The broken lines are for illustrative purpose only and forms no part of the claimed design.
